UNITED STATES PATENT OFFICE.

EUGENE DAUCHER, OF NEW YORK, N. Y.

DESIGN FOR A PINCUSHION.

No. 39,579.

Specification for Design.

Patented Sept. 22, 1908.

Application filed June 26, 1908. Serial No. 440,581. Term of patent 7 years.

To all whom it may concern:

Be it known that I, EUGENE DAUCHER, a citizen of the United States, residing at New York, in the county of New York and State of New York, have invented a new, original, and ornamental Design for Pincushions, of which the following is a specification, reference being had to the accompanying drawing, forming part thereof.

The figure is a perspective view of a pincushion showing my new design.

I claim:

The ornamental design for a pincushion as shown.

EUGENE DAUCHER.
